UNITED STATES PATENT OFFICE.

JOHN T. LINDSTROM, OF ALLENTOWN, PENNSYLVANIA.

STEAM AND OIL SEPARATOR.

SPECIFICATION forming part of Letters Patent No. 699,691, dated May 13, 1902.

Application filed November 9, 1901. Serial No. 81,733. (No model.)

To all whom it may concern:

Be it known that I, JOHN T. LINDSTROM, a citizen of the United States, residing at Allentown, in the county of Lehigh and State of Pennsylvania, have invented new and useful Improvements in Steam and Oil Separators, of which the following is a specification.

My invention has relation to improvements in steam and oil separators of that kind particularly adapted for association with and connection to a steam-engine cylinder, whereby the exhaust-steam may be separated from the oil or lubricant and purified for subsequent use and return to the boiler.

The object of the invention is to provide an apparatus or device of the kind named and for the purpose mentioned which is of simplified and improved construction and which is certain and efficient in the accomplishing of the purposes.

I have fully and clearly illustrated the invention in the accompanying drawings, where-

in—

Figure 1 is a view in elevation showing a steam - cylinder of a steam - engine with my improved steam and oil separator connected to the exhaust-pipe. Fig. 2 is a vertical central view of my improved apparatus, showing the interior elements arranged in operative relation therein. Fig. 3 is a top plan view of the layers of oil-separating bars.

Referring to the drawings, A designates a steam - cylinder; B, the engine - shaft; C, a steam-pipe leading into the steam-cylinder, and D an exhaust-steam pipe leading from the steam-cylinder into my improved apparatus. These elements are illustrated conventionally and may be of any approved construction and arrangement. The steam-cylinder shown is designed to represent a steam-cylinder taking exhaust-steam from a primary steam - cylinder in a double - acting steam-engine; but it is apparent that my improved steam and oil separator may be advantageously connected to the exhaust of a single-acting engine.

In Fig. 2 is illustrated my improved steam and oil separator, the parts being shown in central vertical section, and, reference being had thereto, 1 designates a casing, preferably cylindrical and of such dimensions and capacity as will accommodate it to the pur-

poses and uses intended. The casing or body is formed with annular flanges *a b* at its upper and lower ends, as shown, and at a convenient location adjacent to its lower end is provided with an opening *c*, to which is fitted a steam-tight closure *d*, whereby access may be had to the interior for removing depositions and cleaning the cylinder. The cylinder is provided with a bottom *2*, having an annular flange *e* coincident with the flange *b*, and the bottom is made concave in its inner side to serve as a basin for the condensations. The flanges *b* and *e* are secured together by any proper fastenings. A flanged cover *3* is secured over the casing, and a relief-valve *f* may be placed in the cover. The casing thus made up is mounted on a suitable support *4*. In the casing is placed a pipe *6*, curved downward and projecting toward the bottom of the casing. The entrance end of the pipe *6* projects beyond the face of the casing and is provided with an annular flange *g*, adapted to be secured to the flanged end of the exhaust-pipe *D*. The pipe *6* may be held tight to the cylinder by inner and outer flanges *h h'* and a suitable packing *i* between the inner flange and the inner face of the casing. In the casing, at a suitable and determined distance above the bottom thereof, are arranged layers of bars *26*, semicircular in cross-section and placed across the casing in vertical series or layers, one above the other, with spaces between their side edges and the spaces of lower layers being covered or straddled by the bars of the next adjacent and succeeding layer, as shown in the drawings. The ends of the bars are supported on the inwardly-extending flanges of bands *27*, secured at intervals to the inner face of the casing. The nest or series of bars thus arranged and mounted constitute the means for effecting the separation of the steam from the oil or lubricant, which is accomplished by the tortuous or zigzag passage of the steam through the spaces between the bars, the oil adhering to the bars and accumulating thereon until it drops by gravity into the chamber below, while the steam, purified by the elimination of the oil, passes upward. The steam-pipe *6* extends through the oil-separating bars, as shown, and discharges into the chamber below them, from whence the steam rises and is forced through

the tortuous passages between the said bars. In the upper portion of the casing is placed a dry pan or box 10, provided with a perforated cover or top K, through which the steam has 5 access to the pan. Secured to the bottom of the dry-pan and opening therefrom is a curved exhaust-pipe 14, having its lower end extended through and beyond the casing, as at 15, and is suitably formed to connect to a pipe (not 10 shown) which leads to a condenser or heater for subsequent use in the boiler. The pipe 11 is held in position by oppositely -arranged flanges m n and interposed packing-ring, or in both instances the pipes 6 and 11 may be 15 secured in position by the flanges h' and m and suitable packing behind them and a coupling-piece then secured to the outer faces. Means are provided for automatically discharging the accumulations of condensations of water 20 and oil from the casing. In the bottom of the casing is fitted a bushing or plug 21, having the upper end ground tapering, as at o, to form a seat for a sleeve, as hereinafter specified. In the bushing 21 a vertical tube 20 is fitted 25 and held. This tube is closed at its upper end and provided with an escape-port 25, placed closely adjacent to the upper end of the bushing 21, so that the water of condensation and the oil will escape and be discharged through 30 the tube 20. On the tube 20, within the casing, is slidingly arranged a sleeve 22, having its lower end shaped to fit tight down on the end of the bushing 21 to prevent leakage. The sleeve 22 is projected through a float 23, 35 so that the sleeve will be moved with the movements of the float. It will be perceived from the foregoing that when the products of condensation are below the escape-orifice the float will hold the end of the sleeve down 40 on its seat on the end of the bushing, and the condensations cannot escape; but when the condensations rise to lift the float, with the sleeve, above the escape-orifice the products of condensation escape and continue to dis- 45 charge until by the descent of the float, with the sleeve, the escape-orifice is closed. To draw off whatever of residuum may accumulate in the casing below the orifice 25 a pipe 24 is provided, which leads into the lower 50 end of the tube 20 and is provided with a suitable valve p to open and shut the passage through the pipe.

The operation of the apparatus is as follows: The exhaust-steam from the engine is 55 fed through the pipe 6 and discharges into the casing into the chamber below the oil-separating bars, from which the steam rises, and during its tortuous passage through the nest of oil-separating bars is deprived of the asso- 60 ciated oils, which when accumulated sufficiently drip into the lower part of the casing.

The steam continuing its upward course reaches the top or cover of the casing, where it is deflected into the dry-pan through the perforations in its cover and escapes com- 65 paratively dry and purified through the pipe 11 to a condenser, heater, or, where desired, ready and cleaned for use in the boiler.

Having thus described my invention, what I claim as new, and desire to secure by Letters 70 Patent, is—

1. A steam and oil separator, comprising a suitable casing, a nest of transversely -arranged bars in the casing laid in vertical series and having spaces between them, the 75 bars of each succeeding layer intersecting the spaces of the layer below, a steam-pipe entering the casing above and discharging below the nest of bars, a steam-box disposed in the upper portion of the casing having 80 inlets in its top, and a steam-outlet pipe leading from the steam-box above the nest of bars.

2. A steam and oil separator, comprising a suitable casing, a nest of transversely-laid 85 bars in the casing placed in vertical series and having spaces between them, the bars of each succeeding layer intersecting the spaces of the layer below, a steam-pipe entering the casing above and discharging be- 90 low said bars, a steam-box having a perforated cover or top, in the upper portion of the casing, and a steam-outlet pipe leading from the bottom of the steam-box through the wall of the casing. 95

3. A steam and oil separator, comprising a suitable casing, a nest of transversely-laid bars in the casing, semicircular in cross-section and placed in vertical series with spaces between them, the bars of each succeeding 100 layer intersecting the spaces of the layer below, a steam-pipe entering the casing above and discharging below the said bars, a steam- 105 box in the upper portion of the casing, having a perforated cover, a steam-outlet pipe leading from the steam-box through the casing, and means in the bottom of the casing to draw off the water of condensation and the oil.

4. A steam and oil separator, comprising a 110 casing, separators arranged therein, a steam-pipe discharging beneath the separators, a steam-box disposed in the casing above the separators and provided with steam-inlets, and a steam -discharge leading from the 115 steam-box out of the casing.

In testimony whereof I affix my signature in presence of two witnesses.

JOHN T. LINDSTROM.
